UNITED STATES PATENT OFFICE.

JAMES E. McCONNELL, OF WOLVERTON, AND WILLIAM SEATON, OF REGENTS PARK,
ENGLAND.

CONSTRUCTING PERMANENT WAYS OF RAILROADS.

Specification of Letters Patent No. 19,483, dated February 23, 1858.

To all whom it may concern:

Be it known that we, JAMES EDWARD McCONNELL, of Wolverton, in the county of Buckingham, England, civil engineer, and 5
WILLIAM SEATON, of Chester Place, Regents Park, in the county of Middlesex, England, gentleman, have invented certain Improvements 10
in the Form and Construction of the Permanent Way of Railways, and that the following is a full, clear, and exact description 15
of the principle or character which distinguishes them from all other things before known and of the usual manner of making, modifying, and using the same.
15 These improvements refer to the construction of lines with continuous longitudinal sleepers or bearings. The rails themselves have a solid or flat sided top or a top of such a section that the rail may be rolled 20
on its top and bottom or on its foundation and wheel bearing surfaces. This rail has a rectangular bearing on the angular or double inclined surface of a continuous or longitudinal sleeper which is of a right angled 25
triangular section with a flat base to rest on the ballast while its angular apex or ridge is upward and bears the base of the rail which is rolled with a corresponding double incline or angular recess to fit it. This right angled triangular longitudinal sleeper is 30
formed out of a square sectioned length of timber by cutting it diagonally either in one or both directions so as to make two or four triangular sleepers out of one square 35
sectioned baulk thereby effecting a great saving in material and labor. Cross ties of a similar section and of about one fourth the sectional area are placed under the sleepers with their apices downward and the 40
whole are pinned or otherwise secured together in any convenient manner to maintain the proper gage of the road. A triangular metal joint piece is inserted into the apex of the sleeper under the joint of each rail thereby giving greater solidity and 45
support to the rail ends.

In cases where large square timber cannot be found we substitute rough semicircular timber formed by sawing the trunks or large 50
straight branches of trees longitudinally down the center. The top or rounded surface is then cut flat or rounded off by means of an adz or other convenient cutting tool so as to receive the base of the rail which may

either be the ordinary bridge rail or the girder 55 rail. The flat side of this semicircular longitudinal sleeper is laid downward onto the ballast and rests upon rough semicircular cross ties having their rounded sides placed downward. This rounded form of sleeper 60 placed with its flat side downward has the advantage of affording greater solidity and also of protecting or preserving the rail by throwing off the wet. A flat metal joint piece may be inserted in the sleeper under 65 the joint of each rail to support the rail ends. And in order that our invention may be clearly understood we shall now proceed more particularly to describe the same and for that purpose we shall refer to the several 70 figures on the sheets of drawings hereunto annexed.

Figure 1 on Sheet 1 of our drawings represents a transverse section of our right angled triangular longitudinal sleeper with 75 its rail and joint piece attached.

A is the sleeper B the rail and C the triangular joint piece which passes under the end of each rail and is let into a recess formed to receive it on the apex or ridge of 80 the sleeper as shown in Fig. 2 which represents a longitudinal section of a portion of the rail and sleeper at the joint. This sleeper is formed by cutting a square baulk diagonally from corner to corner the outline 85 of the lower portion of the square baulk w w w being shown by the dotted lines a, a, in Fig. 1.

D, D, are screw pins which are passed through holes in the flanges E, E, of the rail 90 and are screwed into the body of the sleeper, the points of the pins converging so as to produce a firm and secure fastening.

Fig. 3 represents a baulk of square timber cut diagonally into four triangular 95 sleepers A, A, A, A and the dotted lines a, a, a, a, represent the same sized square baulk used in the ordinary manner. On referring to this figure it will be observed that by cutting the square baulk into two 100 sleepers as in Fig. 1 a larger bearing or base is given to the sleeper with a saving of one half of the timber and that by cutting the baulk into four sleepers each sleeper will have the same amount of bearing or 105 base as the original baulk thereby obtaining four sleepers in place of two with a saving of three fourths of the timber. Two of the

smaller triangular sleepers A may be combined to form one large sleeper in which case the smooth inner sides may be turned outwardly and the rough sides which formed 5 the sides of the original square baulk are placed inwardly the peculiar form of the rail bearing serving to grip the two halves together which are further secured and held together by the pins or screws which pass 10 through the flanges of the rail and into the opposite halves of the sleepers.

Fig. 4 represents a side elevation of a portion of a permanent way laid down and constructed according to our invention with 15 right angled triangular longitudinal sleepers and cross ties. Fig. 5 is a corresponding transverse section of the same and Fig. 6 is a plan of a portion of the road complete.

A are the sleepers B the rails C the cross 20 ties which are fixed at suitable intervals along the under side of the sleepers.

We are aware that railways constructed on a plan similar to ours have been suggested but never were carried out into practice 25 on account of the shape of the rails, the rolling of which is beyond the means of ordinary rolling-mills. Fig. 1. Sh. 3, shows a rail constructed upon the suggested plan. Fig. 2, a rail of our own construction and 30 effectually carried out into practice and Fig. 3, a pair of rollers exhibiting the manner of rolling said rails.

Fig. 1 on Sheet 2 of the drawings represents a transverse section of a longitudinal 35 sleeper formed out of a rough uncut piece of timber by splitting it up the middle and laying the flat side downward and the upper rounded side being dressed off either round as shown in the drawing or flat. When 40 round the base of the rail, which in the drawing is of the bridge form, is slightly curved to correspond.

The dotted line *a* completes the outline of the tree or uncut baulk of timber as it exists 45 before being sawed down the middle.

The rails shown in drawing No. 2 are of a peculiar construction; the wheel bearing surface on top and sides of the rail are similar to those of ordinary U or bridge rails, 50 while the flanges are bent down and rounded off so as to correspond with the sectional periphery of a round piece of timber. By this means the wet is thrown off more freely and the pins or rail fastenings by being inserted

so as to converge slightly will be less liable 55 to be accidentally loosened or withdrawn.

Fig. 2 is a longitudinal section of the rail and sleeper showing the flat metal joint plate A for supporting the rails at the joints. Fig. 3 is a side elevation of a portion of the 60 roadway laid with the rough semicircular sleepers and cross ties. Fig. 4 is a transverse section of the same and Fig. 5 is a plan of a portion of the roadway complete.

A are the sleepers B the rails C the cross 65 ties which are of the same form and construction as the sleepers but are cut out of smaller timber.

The peculiar but simple construction of permanent way hereinbefore last described 70 will be found highly advantageous in other parts of the country where machinery of any kind is difficult of transport.

We propose in all cases where possible to insert a layer of felt or other soft or yielding material between the rail and the sleeper for the purpose of imparting a certain degree of elasticity to the road and the same time deaden the unpleasant noise and vibration occasioned by the passage of the train 80 over it, this is particularly applicable to the triangular sleeper.

Having now described the nature of our invention and the mode of carrying the same into effect we may here observe that what 85 we consider to be novel and original and forming the main features of this invention is,

The system or mode of constructing the permanent way of railways herein described, 90 consisting in the use of rightangled triangular longitudinal sleepers and crossties in combination with wrought iron rails when the latter are constructed on the plan herein specified and when all the parts constituting 95 the railway are united together and arranged in relation to each other in the manner and for the purposes set forth.

In witness whereof we the said JAMES EDWARD McCONNELL and WILLIAM SEATON 100 have hereunto set our hands and seals the sixth day of April one thousand eight hundred and fifty seven.

J. E. McCONNELL. [L.S.]
WILLIAM SEATON. [L.S.]
